INTERIOR TRAY FOR ELECTRIC HAIR DRYER

Louis J. De La Marter, Lexington and Frederick W. Perl, Mansfield, Ohio, and Joseph R. Mango, Midlothian, Ill., assignors to Westinghouse Electric Corporation, a corporation of Pennsylvania

Filed June 4, 1962, Ser. No. 70,388

Term of patent 14 years

(Cl. D86—10)

Fig. 1.

Fig. 2.

Fig. 3.

FIG. 1 is a perspective view of an interior tray for electric hair dryer, showing our new design;

FIG. 2 is an enlarged scale fragmentary front elevational view of the fingernail dryer incorporated in FIG. 1; and

FIG. 3 is an enlarged scale fragmentary section taken on the line III—III of FIG. 2.

The dominant features of the design reside in the portions shown in full lines.

We claim:

The ornamental design for an interior tray for electric hair dryer, substantially as shown and described,
